JOHN H. BARR, OF ITHACA, NEW YORK, ASSIGNOR TO BARR-MORSE CORPORATION, A CORPORATION OF NEW YORK.

PLATEN-ADJUSTING MECHANISM.

Application filed October 7, 1925. Serial No. 60,974.

This invention relates to platen adjusting mechanism for typewriters, adding machines and similar devices. In such devices, the platen is usually line-spaced by a ratchet wheel that is driven or manipulated by suitable mechanism, the platen and ratchet wheel being coupled in a suitable manner enabling their disconnection from one another and thereby permitting separate rotation of the platen. It is frequently desirable, particularly in typewriting machines, to adjust the platen independently of the driving ratchet wheel, as when positioning the paper or sheet being printed upon so that the printing will occur in any particular part of the sheet or paper, and after such adjustment to effect a recoupling of the ratchet wheel to the platen so that the ratchet wheel will properly space or rotate the platen angularly through the usual spacing increments from the newly adjusted position. Heretofore, such adjustment has been commonly controlled by special added appliances which increased the number of parts and thereby increased the cost of manufacture, and with whose use an operator must become familiar. With prior devices it has often been necessary to utilize both hands when making such an adjustment, one to release the platen and the other to turn it after release. There was no provision for taking up wear, and when a coupling or uncoupling of the platen and ratchet wheel was controlled by an element shiftable in a direction lengthwise of the platen, and the ratchet wheel was disposed at the left hand end of the platen, it has been usually necessary to hold the carriage while the controlling element was shifted to release the platen.

An object of this invention is to provide an improved platen adjusting mechanism, with which an operator may, with one hand, without holding the carriage, and by engaging a single part, release the platen from its operating mechanism and adjust it to any desired angular extent and then recouple it to the ratchet wheel in such adjusted position; with which no additional controlling or operating handles or parts will be required; which will have a satisfactory, dependable, and adjustable driving connection between the ratchet wheel or operating mechanism and the platen; with which the extent of the friction of coupling may be varied to suit individual desires or to compensate for wear; which will be com-

pact, convenient, dependable, easily manipulated, simple, and relatively inexpensive.

Various other objects and advantages will be apparent from the following description of one embodiment of the invention, and the novel features will be particularly pointed out hereinafter in connection with the appended claims.

In the accompanying drawing:

Fig. 1 is a sectional elevation through a typewriter carriage and platen having an adjusting mechanism constructed in accordance with this invention; and

Fig. 2 is an end elevation of the same.

In the illustrated embodiment of the invention a platen shaft 1 is rotatably and slidably mounted in bearings 2 and 3 supported in frame brackets or members 4 of the carriage, the bearings being preferably removably carried by said brackets 4 in order to enable the removal of the platen when desired. Any suitable means (not shown) for locking the bearings to the frame 4 may be employed. A platen cylinder 5 surrounds the platen shaft 1 and may be provided with end walls 6 and 7 which are removably attached thereto in any suitable manner, such as by screws 8 which pass through the end walls and into engagement with the ends of the cylinder 5. The cylinder 5 carries the usual or any suitable platen or roller printing surface.

The end wall 6 of the cylinder is provided with an inwardly extending hub portion 10 which slides along and upon the shaft 1. The hub portion 10 is provided with a longitudinally extending slot 11 and the shaft 1 is provided with a transversely extending pin 12 which engages in said slot 11, so as to provide a keyed connection between the platen cylinder and shaft and cause their concomitant rotation while permitting independent endwise movement of the platen shaft. A single slot 11 may be employed with the pin 12 projecting only from one side of the shaft, but preferably and for various reasons, such as because of manufacturing advantages, two slots 11 are provided upon diametrically opposite sides of the hub portion and the pin 12 projects diametrically from opposite sides of the shaft and into both slots 11. The outer face of the end wall 6 may be provided with a recess 13 for receiving a flange 14 provided upon a portion of the bearing 2 and which projects along the shaft

1 from the portion of the carriage frame 4 to which it is attached.

A plate 15 is fitted against the outer face of the end wall 6 of the cylinder and is secured thereon by screws 8 which secure the end wall to the cylinder. The plate 15 fits over the bearing 2 and against the flange 14 so as to prevent its removal from the recess 13. The flange 14 of the bearing 2 is thus coupled to the end wall of the platen cylinder in such a manner as to prevent endwise movement of the platen cylinder while permitting free rotation of the cylinder and its end wall 6. The plate 15 may be formed, either in two sections to enable it to be fitted around the bearing 2, or it may have a slot from one edge thereof of a width corresponding to the diameter of the bearing 2 so that it may be slid over the same.

20 The end wall 7 of the cylinder is provided with an aperture 16 surrounding and larger than the shaft 1, in which aperture a sleeve 17 slideable upon the shaft 1 is also slideable endwise to various extents therethrough. 25 The sleeve is provided at its inner end with an outwardly peripheral flange 18, and at its outer projecting end is screw threaded as at 19. A ratchet wheel 20 is threaded upon the outer end of the sleeve 17 and locked in various adjusted positions thereon by a nut 21, also threaded upon the threaded end of the sleeve 17. The outer end of the sleeve is preferably provided with one or more notches 22 for receiving a suitable tool, whereby the sleeve may be held against rotation while the ratchet wheel and nut are being threaded therealong to various extents.

30 The ratchet wheel, upon its face abutting the end wall 7 is provided with an annular groove 23 somewhat V-shaped in cross section, and the corresponding abutting face of the end wall 7 is provided with an annular rib 24 also somewhat V-shaped in cross section and of such a size as to fit within the groove 23. The rib 24 and groove 23 thus, in effect, serve as a frictional clutch between the ratchet wheel and the cylinder, the V-shape increasing the frictional surface and resistance between them and also compensating for wear during use. Furthermore, by the use of the V-shape for the groove and rib, there is a somewhat wedge-like action between the walls of the groove and the rib when the ratchet wheel is moved endwise, thus providing a more effective frictional coupling between the ratchet wheel and cylinder.

35 The end wall 7, upon its inner face is provided with bearing ears 25 upon which bell crank clutch levers 26 are pivoted by pins 27. Each lever 26 has a shorter arm 28 which extends transversely of the shaft 1 and engages behind the flanged head 18 of the sleeve 17. The other and longer arms of the levers 29 extend along the shaft 1 within the cylinder

40 and engage with the tapered cam surface 30 of an abutment element 31 which is slideable upon the shaft 1 within the cylinder. A helical compression spring 32 is provided upon the shaft 1 within the cylinder and bears at 45 one end against the flanged head 18 of the sleeve 17 and at its other end against the cam element 31, so as to normally urge the cam element in a direction to separate, by a wedging action of the tapered cam surface, the 50 long clutch arms 29 of the clutch levers.

55 A pin 33 carried by the shaft 1 within the cylinder may be provided to force the cam element endwise against the action of its spring and release the clutch levers when the 60 shaft 1 is shifted endwise, that is to the left in Fig. 1. The shaft 1, at both ends, is provided with an operating button 34 by which it may be rotated and also shifted endwise from the full line position shown in Fig. 1, 65 where the ratchet wheel and platen cylinder are coupled, to the dot and dash position also shown in the same figure and in which the ratchet wheel and cylinder are uncoupled. The spring 32 will always hold the abutment element or wedge 31 against the pin 33 and, therefore, the wedge or abutment element 31 could just as well be formed as an integral part of the platen shaft 1 or be pinned thereto so far as its operation is concerned. However, the assembly of the mechanism of the platen is simpler when the abutment or wedge element is freely slideable upon the platen shaft and abutting against the pin 70 33, as illustrated, and for that reason this illustrated construction is somewhat preferable.

75 Considering the operation of this mechanism, the normal position of the various parts is shown in the drawings in full lines, the shaft 1 being urged to its furthest position to the right by the spring 32 acting thereon through the cam element 31 and the pin 33. In this condition of the parts, the cam element 31 has wedged the clutch lever arms 29 apart, so that the shorter arms 28 of the levers 26 will pull the sleeve 17 inwardly. The sleeve in moving inwardly will carry the ratchet wheel into frictionally coupled engagement with the end walls 7 of the cylinder and, therefore, whenever the ratchet wheel is operated, its motion will be transmitted to the platen cylinder and the printing surface 9 thereof.

80 While the spring 32 acts at one end to shift the sleeve 17 in one direction and at its other end through the cam element and levers 26 to shift the sleeve in the other direction, it will be observed that since it operates at one end through the longer arms 29 of the levers 26, the net result will be that it will hold the clutch levers separated. The operator may manually rotate the platen element by merely turning the button 34 in a rotary direction.

85 If the operator now wishes to disconnect 90

the platen element from the ratchet wheel he will merely shift the platen button 34 to the left into the dot and dash lines shown on the drawing, during which movement the 5 shaft 1 will be shifted endwise. The pin 33 of the shaft 1 during such movement will force the cam element 31 to the left in Fig. 1, against the action of the spring 32 and thus release the sleeve 17. The sleeve 17 will 10 then move outwardly sufficiently to release the pressure between the abutting faces of the ratchet wheel and end wall 7 and as a result, there will be no driving friction between them. Rotation of the button 34 while 15 in its new endwise position will thus rotate the platen element without moving the ratchet wheel.

It will be observed that the platen shaft is always rotatably coupled to the platen cylinder through the pin 12 which has a keyed relation with the end wall 6 of the cylinder. Upon a release of the platen knob it will be forced endwise to its full line position by the spring 32 which shifts the shaft 25 1 endwise through the cam 31 and pin 33. The cam 31 in moving with the shaft 1 to the full line position will force the arms 29 of the clutch levers apart, draw the sleeve 17 inwardly, and force the ratchet wheel 7 into frictional engagement with the end wall 9 of the platen element, thus effecting a recoupling of the ratchet wheel and platen element. Then when the ratchet wheel is given increments of movement, these increments will 35 be imparted to the platen printing surface 9 starting from the newly adjusted position.

The ratchet wheel 20 is preferably mounted at the left hand end of the platen, and since movement of the carriage to the left, 40 as usual, is controlled by the escapement, the latter will hold the carriage stationary while the platen shaft is given endwise movements in effecting an uncoupling of the platen and ratchet wheel, and thus it is merely necessary for a typist to employ but one hand in 45 releasing and turning the platen in making an adjustment. The carriage will not be unintentionally back spaced, as is often the case where an uncoupling of the platen from the ratchet wheel is accomplished by an element 50 that moves in a back spacing direction on the carriage.

By providing for the adjustment of the ratchet wheel, great accuracy in the manufacture 55 of the various parts is unnecessary, and thus the production cost is lowered. Since the arms 28 are short, relatively to the arms 29, a slight variation in the edges of the arms 28 which engage the flange 18 will be greatly amplified at the free ends of the long arms 60 29. With this invention, the parts may be produced by the least expensive operations, and after assembly a simple adjustment of the ratchet wheel 20 and the nut 21 upon 65 the sleeve 17 will compensate for any varia-

tions in the other parts of the coupling mechanism.

It will be observed that the disconnection of the platen element from the ratchet wheel, and its rotation or adjustment to new positions, is accomplished entirely by the single operating button 34, so that special platen adjustment members, or operating or controlling parts are unnecessary. Thus the number of parts necessary for the manipulation of the device is reduced to a minimum without sacrificing any of the advantages of the adjustment, and the adjustment of the platen may be obtained by an operator with the use of only one hand and in a very simple and convenient manner. The coupling obtained in this manner between the ratchet wheel and platen is very efficient, dependable, durable and the entire construction exceptionally simple and relatively inexpensive. 70 75 80 85

It will be obvious that various changes in the details, which have been herein described and illustrated for the purpose of explaining the nature of the invention, may be made by those skilled in the art within the principle 90 and scope of the invention as expressed in the appended claims.

I claim:—

1. In platen adjusting mechanism, a platen shaft, spaced apart bearings supporting said shaft for endwise and rotary motion, a platen core disposed on said shaft between said bearings and coupled to said shaft in such a manner that the platen will always be rotated upon rotation of the shaft and the shaft may be shifted endwise without interruption of the driving connection between it and the core, a ratchet wheel, a sleeve slidable and rotatable on said shaft and mounting said ratchet wheel, and means controlled by endwise movement of the shaft for drawing said sleeve into said core to frictionally couple the ratchet wheel and core for concomitant rotation, and operable to cause a release of said sleeve when disconnection of the ratchet wheel and platen is desired. 95 100 105 110

2. In a platen adjusting mechanism, a platen shaft, means for mounting said shaft for endwise and rotary motion, a platen core through which the shaft passes and coupled to said shaft for concomitant rotation therewith while permitting independent endwise movements of said shaft, a sleeve slidable and rotatable on said shaft and extending through an end of said core, a ratchet wheel mounted upon the outer end of said sleeve so as to be movable with said sleeve against and away from an end wall of said platen core, clutch levers acting between the sleeve and core for drawing said sleeve into the core to frictionally couple the ratchet wheel and core, and means controlled by the endwise movements of the shaft for operating said clutch levers. 115 120 125

3. In a platen adjusting mechanism, a platen shaft, means for mounting said shaft 130

- for endwise and rotary motion, a platen core through which the shaft passes and coupled to said shaft for concomitant rotation therewith and permitting independent endwise movements of said shaft, a sleeve slidable and rotatable on said shaft and extending through an end of said core, a ratchet wheel mounted upon the outwardly projecting portion of said sleeve so as to be movable with said sleeve 5 against and away from the end wall of said platen core, clutch levers acting between the sleeve and core for drawing said sleeve into the core to frictionally couple the ratchet wheel and core, a cam movable in a direction 10 along the axis of the shaft and having a cam surface controlling said clutch levers, a spring acting upon said cam member to urge it in a direction to cause a coupling operation of said clutch arms, and means operable by the shaft during an endwise movement for operating the cam element against the action of said spring in a direction to release the sleeve and permit of separation of the ratchet wheel and platen core.
26. 4. In a platen adjusting mechanism, a platen shaft, means for mounting said shaft for endwise and rotary motion, a platen element coupled to said shaft for rotation therewith, a ratchet wheel, clutch means acting between the platen element and ratchet wheel for causing relative movement of said platen element and ratchet wheel into and out of driving engagement with one another, said clutch means including relatively movable parts, one of said parts having a section adjustable thereon independently of the said relative movement to compensate for wear, means normally urging said clutch means in a manner to cause coupling of the ratchet wheel and platen element, and means operable by the shaft during an endwise movement independently of the platen for causing operation of said clutch means to uncouple the ratchet wheel and platen element and permit of their independent relative rotation.
46. 5. In a platen adjusting mechanism, a platen element and a ratchet wheel element relatively movable into and out of coupled engagement with one another, one of said elements having two sections, means acting between one of said sections and the other element to produce relative movement and effect a coupling between the other of said sections and said other element, said one of said sections being adjustable on the first section independently of such relative movement to facilitate adjustment of said element relatively to one another, and means for causing relative movement of said elements to couple or release them.
66. 6. In a platen adjusting mechanism, a platen shaft, means for mounting said shaft for endwise and rotary motion, a hollow platen element coupled to said shaft for rotation therewith and permitting independent

endwise movement of said shaft, a ratchet wheel, a supporting element for said ratchet wheel passing into the interior of said platen element, levers carried by one of said elements and having arms acting upon the other of said elements to draw them into coupled engagement with one another, and also having operating arms extending along the platen shaft, a wedge carried by said shaft and acting upon said operating arms of the levers to effect a coupling of the ratchet wheel and platen element, a spring acting to shift said wedge in a direction to cause a coupling of the ratchet wheel and platen element, said wedge being movable by an endwise movement of the shaft against the action of the spring in a direction to release the operating arms and thereby effect a disconnection of the driving relation between the ratchet wheel and platen element.

7. In a platen adjusting mechanism, a platen shaft, means mounting said shaft for endwise and rotary motion, a platen cylinder having end walls through which the shaft passes, one of said end walls having a connection to said shaft, such that the shaft may be movable endwise independently of the platen and while remaining rotatably coupled thereto, means for preventing endwise movement of said platen with the shaft, a sleeve surrounding the shaft and passing through an end wall of the platen cylinder, a ratchet wheel carried by said sleeve exteriorly of the cylinder and movable with the sleeve toward and from the end wall of said cylinder through which the sleeve passes, levers carried by said cylinder and having arms engaging with said sleeve to pull the ratchet wheel against the end wall of the cylinder, said levers having relatively longer operating arms extending along the shaft within the cylinder, a wedge carried by the shaft and having a tapered-cam surface for separating said lever arms which extend along the shaft and thereby cause an inward movement of the sleeve, a spring surrounding the shaft and acting between the sleeve and the wedge for normally urging the wedge in a direction to effect a coupling of the ratchet wheel and cylinder, said shaft and wedge having coacting portions to cause their movement together when the shaft is shifted in one endwise direction to release the operating arms of said levers and thereby effect a disconnection between the ratchet wheel and cylinder.

8. In a platen adjusting mechanism, a platen shaft, means mounting said shaft for endwise and rotary motion, a platen cylinder having end walls through which the shaft passes, one of said end walls having a connection to said shaft, such that the shaft may be movable endwise independently of the platen and while remaining rotatably coupled thereto, means for preventing endwise movement of said platen with the shaft, a sleeve surrounding the shaft and passing

- through an end wall of the platen cylinder, a ratchet wheel mounted on said sleeve and adjustable lengthwise of the same, levers carried by said cylinder and having arms engaging with said sleeve to pull the ratchet wheel against the end wall of the cylinder, said levers having relatively longer operating arms extending along the shaft within the cylinder, a wedge carried by the shaft and having a tapered cam surface for separating said lever arms which extend along the shaft and thereby cause an inward movement of the sleeve, a spring surrounding the shaft and acting between the sleeve and the wedge for normally urging the wedge in a direction to effect a coupling of the ratchet wheel and cylinder, and an abutment carried by the shaft and engageable with the wedge during endwise movement of the shaft in one direction to force the wedge in a direction to release the operating arms of said levers and thereby effect a disconnection between the ratchet wheel and cylinder.
9. In a platen adjusting mechanism, a platen shaft, means for mounting said shaft for endwise and rotary motion, a hollow platen element coupled to said shaft for rotation therewith and permitting independent endwise movement of said shaft, a sleeve element slidable on said shaft through the end of said platen element, a ratchet wheel carried by the outer end of said sleeve element so as to be movable with the sleeve element against the end of the platen element, clutch levers carried by one of said elements and acting upon the other element to produce relative movement between said elements and thereby draw the ratchet wheel and the platen element into driving relation with one another, said levers having operating arms extending along the shaft, means for moving said operating arms in directions to couple said ratchet wheel with the platen element or for releasing them, and means including said shaft and a spring for normally urging said means in a direction to effect a coupling of said ratchet wheel and platen element, and operable to effect a disconnection of said ratchet wheel and platen element.
10. In a platen adjusting mechanism, a platen shaft, means for mounting said shaft for endwise and rotary motion, a hollow platen element coupled to said shaft for rotation therewith and permitting independent endwise movement of said shaft, an element movable through the end of said platen element, a ratchet wheel carried by the outer portion of said movable element so as to be movable therewith against the end of the platen element, clutch levers carried by one of said elements and acting upon the other element to produce relative movement between them and thereby draw the ratchet wheel into driving relation with the platen element, said levers having operating arms extending along the shaft, means carried by the shaft for moving said operating arms in directions to either couple said ratchet wheel with the platen element or release them, and a spring normally urging said means in a direction to effect a coupling of said ratchet wheel and platen element, said means and shaft cooperating together to effect a disconnection of said ratchet wheel and platen element upon an endwise movement of the shaft, said shaft supporting means engaging with the platen element to prevent its axial movement with the shaft.
11. In a platen adjusting mechanism, a platen shaft, a carriage frame, bearings provided on said frame and supporting said shaft for endwise and rotary motion, a platen element coupled with the shaft for rotation therewith and permitting independent endwise movement of said shaft, one of said bearing elements having a peripheral flange, said platen element having means cooperating with said flange to prevent endwise movement of said platen element while permitting free rotary movement thereof, a ratchet wheel, means for coupling said ratchet wheel and platen element for rotation together, and means carried by said shaft operating by endwise movements of the shaft for effecting a disconnection of said ratchet wheel and platen element.
12. In a platen adjusting mechanism, a platen shaft, means for mounting said shaft for endwise and rotary motion, a platen cylinder having end walls surrounding said shaft, one of said end walls being coupled to said shaft for rotation therewith and permitting independent endwise movement of said shaft, a sleeve slidable on said shaft and passing through an end wall of said cylinder, a ratchet wheel mounted on the outer end of said sleeve, means within the cylinder for drawing said sleeve into the cylinder and carrying the ratchet wheel into frictional driving relation with an end wall of the cylinder, said last named end wall and said ratchet wheel having upon their abutting faces cooperating V-shaped grooves and ribs for providing a maximum frictional engagement between them and for compensating for wear.
13. In a platen adjusting mechanism, a platen shaft, means for mounting said shaft for endwise and rotary motion, a platen cylinder having end walls surrounding said shaft, one of said end walls being coupled to said shaft for rotation therewith and permitting independent endwise movement of said shaft, a sleeve slidable on said shaft and passing through an end wall of said cylinder, a ratchet wheel mounted on the outer end of said sleeve, means within the cylinder and controlled by said shaft for drawing said sleeve in a direction to carry said ratchet wheel into frictional driving relation with an end wall of the cylinder, a nut carried by said

sleeve for locking said ratchet wheel to the sleeve, the outer end portion of said sleeve having a configuration for receiving a tool whereby it may be held against rotation when said nut and ratchet wheel are shifted endwise along said sleeve toward said platen cylinder.

14. In a platen adjusting mechanism, a platen shaft, means for mounting said shaft for endwise and rotary motion, a platen cylinder having end walls surrounding said shaft, one of said end walls being coupled to said shaft for rotation therewith and permitting independent endwise movement of said shaft, a sleeve slidable on said shaft and passing through an end wall of said cylinder, a ratchet wheel mounted on the other end of said sleeve, means controlled by said shaft during its endwise movements for shifting said sleeve to carry the ratchet wheel into and out of frictional driving relation with an end wall of said cylinder, and a nut carried by the sleeve for locking said ratchet wheel to the sleeve in different adjusted positions along the sleeve whereby the ratchet wheel may be adjusted along the sleeve to compensate for wear and to obtain a desired initial frictional engagement with the platen.

15. In a platen adjusting mechanism, a platen element, a ratchet wheel, a sleeve on which said ratchet wheel is mounted and along which it is adjustable, said sleeve and platen element being relatively movable to cause a frictional coupling or uncoupling of the platen element and ratchet wheel, and means for shifting said sleeve to effect or break a driving connection between said ratchet wheel and platen element.

16. In a platen adjusting mechanism, a platen element, a ratchet wheel, a sleeve on which said ratchet wheel is mounted and along which it is adjustable, said sleeve and platen element being relatively movable to cause a frictional coupling or uncoupling of the platen element and ratchet wheel, and means for shifting said sleeve to effect or break a driving connection between said

ratchet wheel and platen element, said means being controllable from the end of the platen element opposite from the ratchet wheel.

17. In platen adjusting mechanism, a platen shaft, means supporting said shaft for endwise and rotary motion, a platen core coupled to said shaft in such a manner that the platen will always be rotated upon rotation of the shaft and the shaft may be shifted endwise without interruption of the driving connection between it and the core, a ratchet wheel, a sleeve slidable and rotatable on said shaft, said ratchet wheel being mounted on said sleeve for adjustment axially thereof, and means controlled by endwise movement of said shaft for drawing said sleeve into said core to frictionally couple the ratchet wheel and core for concomitant rotation and operable to cause a release of said sleeve when disconnection of the ratchet wheel and platen is desired.

18. In a platen adjusting mechanism, a platen shaft, means for mounting said shaft for endwise and rotary motion, a hollow platen element coupled to said shaft for rotation therewith and permitting independent endwise movement of said shaft, a sleeve element slidable on said shaft through the end of said platen element, a ratchet wheel carried by the outer end of said sleeve element so as to be movable with the sleeve element against the end of the platen element, clutch levers carried by one of said elements and acting upon the other element to produce relative movement between said elements and thereby draw the ratchet wheel and the platen element into driving relation with one another, said levers having operating arms extending along the shaft, and means controlled by endwise movement of said shaft for operating said arms to frictionally couple or uncouple the ratchet wheel and platen element by causing endwise movement of said sleeve element.

In witness whereof, I hereunto subscribe my signature.

JOHN H. BARR,
